Attn:

UNITED STATES PATENT OFFICE.

ANDREW M. NEWLANDS, OF GALT, ONTARIO, CANADA.

DESIGN FOR A CARRIAGE RUG OR ROBE.

SPECIFICATION forming part of Design No. 19,117, dated May 28, 1889.

Application filed March 28, 1889. Serial No. 305,174. Term of patent 7 years.

To all whom it may concern:

Be it known that I, ANDREW MARK NEWLANDS, a subject of the Queen of Great Britain, residing in the town of Galt, in the county of Waterloo, in the Province of Ontario, Canada, manufacturer, have invented and produced a new and original Design for a Carriage Rug or Robe, of which the following is a specification, reference being had to the accompanying drawings, forming part thereof.

Figure 1 is a view of a portion of one side of a rug or robe made in accordance with my design, its edge being turned up to expose the lining or opposite side of the rug or robe. Fig. 2 is a similar view of the opposite side of the said rug or robe.

The object of my design is to produce a rug or robe having one surface made with the appearance of buffalo or other long-haired fur and the other surface in imitation of Persian lamb or other similar curly short-haired fur.

The leading feature of my design consists in a raised surface contrasting in appearance

on the two sides of the fabric, giving the appearance of long-haired fur upon one side and 25 tufted or curly short-haired fur on the other side.

In the drawings, A represents the long-haired side of the rug or robe, similar to buffalo or other long-haired fur, as indicated. 30

B represents the opposite side, the outer surface of which has the appearance of Persian lamb or other short-haired curly fur.

I claim—

The herein-shown design for a fabric de- 35 signed more particularly for a carriage rug or robe, the same having one side in imitation of buffalo or other long-haired fur and the other side tufted in imitation of short-haired curly fur, substantially as shown. 40

Toronto, December 20, 1888.

ANDREW M. NEWLANDS.

In presence of—

CHARLES C. BALDWIN,
I. EDW. MAYBEE.
